VALVE

Grover C. Singer, Brownsville, Tex.

Application May 3, 1951, Serial No. 224,394

3 Claims. (Cl. 138—45)

1

This invention relates to valves, and more particularly to a plunger type valve to be used in connection with oil well equipment.

An object of my invention is the provision of a valve in which the movable plunger head has a plurality of removable orifice dies to be selectively moved into position to permit flow of the oil through the valve unit. These dies are in spaced relationship to one another so that when one die orifice is aligned with the inlet and outlet openings of the valve body the other die is out of operative position.

Another object of the invention is to provide the valve body with removable cover plates located on opposite sides of the flow passage whereby a die when in its inoperative position may be inspected or removed and replaced while a second die is in operative position. This construction prevents the necessity of a shut down of operation when replacing a worn die.

A further advantage of the device is that the movable member, i. e. the reciprocable plunger is provided with appropriate channels for lubricating and sealing the plunger.

These and other objects and advantages will become apparent from the following description of the present invention illustrated in the accompanying drawing, in which:

Figure 1 is a sectional view taken on a vertical plane through the center of the device.

Figure 2 is a side elevational view of the valve head.

Figure 3 is a sectional view taken on line 3—3 of Fig. 2.

Similar reference characters represent similar parts in the several figures.

One of the major factors to be considered in the operation of oil well equipment is the constant damage to those parts of the equipment which confront the flow of the conveyed fluid. The valves used in connection with the well superstructure are in constant need of repair and replacement, due to the fact that grit and other foreign substance carried by the oil under terrific pressure inevitably cut out the orifice inserts, thereby reducing the operational efficiency of the valve and necessitating the complete shut down of the well in order to carry out repair of the unit. The valve shown in Figure 1 of the drawing has been designed to cope with the above difficulty in that provisions are made therein to permit the continuation of well operations while a worn valve insert is being replaced.

The valve body designated generally as 10 comprises intersecting vertical and horizontal

2

sections cast as an integral unit. The lower end 11 of the vertical section is provided with a peripheral flange 12 having a plurality of apertures 13 angularly spaced therein. This permits the attachment of portion 11 to the discharge end of the well pipe. The conveyed oil or gas enters the passage 14, the upper end of which is reduced to form a conical opening 15. This conical opening accommodates a complementary valve seat 16 which is press-fitted into the opening and provided with a reduced central orifice 17.

The upper end 18 of vertical section 10 is of similar construction to the above-described lower end. This too is provided with a peripheral flange 19 and appropriate bolt-receiving apertures 20 in order that the conveying pipe may be continued. The conical valve seat 21 provided on the discharge end of the valve body tapers in the same direction as the inlet valve seat 16. The valve seat is provided with a reduced central orifice 22 which communicates with the center portion of the valve body by means of a funnel recess 23. The wide receiving end of recess 23 permits proper operation of the valve without the absolute necessity of perfect alignment between the valve head orifice and the discharge orifice 22.

The horizontal section 24 of the valve body is basically a cylindrical sleeve having an opening extending completely therethrough and of uniform diameter. The right-hand horizontal section 25 (as viewed in Figure 1) has its open end provided with a peripheral flange 26 containing appropriate apertures to permit a cover cap 27 to be attached by means of appropriate bolts 28 to properly seal the transverse passageway 29. The left-hand section 30 is also provided with a peripheral flange 31 having spaced apertures therein to permit the attachment of the conical bonnet 32 and intermediate closure cap 33 by means of bolts 34, as shown in the drawing.

It is pointed out that a convenient method of fabricating the valve unit is to weld nipples of drilling tube or pipe to opposite sides of a heavy stock of steel and then rounding out the inside of the steel cylinder after the welding has been completed.

A reciprocable valve head 35 fits within the transverse opening 29 and this valve head is provided with a plurality of conical shaped openings 36 to accommodate complementary insert dies 37. The preferred construction is shown in Fig. 1 which shows the use of two spaced inserts. It will of course be understood that the use of

more than two of these units would not be a departure from the invention.

The construction of dies 37 is basically similar to the removable valve seats. Each die is in the shape of a cone frustum and is provided with a central orifice 38 and a funnel shaped connecting recess 39. As will be seen from Fig. 1 of the drawing, the metering orifices 17, 38 and 22 may respectively communicate without the necessity of perfect alignment of the valve head due to the fact that the various funnel shaped recesses will appropriately channel the oil or gas through the associated elements.

The valve head is provided with a cylindrical stem 40 having an inner threaded end 41 permitting the stem to rigidly engage the movable valve head. The intermediate portion of the valve stem is of smooth cylindrical stock so that the stem can penetrate a central hub 42 formed in the closure plate 33. Hub 42 has an axial opening therein, the surface of which is provided with an appropriate number of annular sealing rings 43 which permit the escape of oil from the valve body.

It will be noted that the outer end 44 of the valve bonnet 31 is provided with a smooth axial opening which rotatably accommodates an operating nut 45. A peripheral flange 46 prevents outward movement of the nut and the main body portion of nut 45 is provided with male threads to cooperate with a female threaded section of hand wheel 47 whereby the hand wheel and nut may be secured together for simultaneous rotation. The extreme outer portion 48 of the nut has a reduced threaded section adapted to receive the lock nut 49 which bears against the outer surface of hand wheel 47 to firmly lock the hand wheel and nut together. Naturally nut 45 has a threaded aperture extending axially therethrough so that the outer threaded end 50 of the valve stem may be received by the operating nut. Thus it will be seen that rotation of the operating handle causes the valve stem to move laterally in a selected direction.

In order to prevent rotation of stem 40 (and accordingly valve head 35) I have incorporated the use of a key and key-way arrangement. The particular location of the key is not critical and for the purpose of illustration I have provided the valve bonnet with a small aperture perpendicular to the axis of the operating stem. This aperture being threaded receives a threaded key 51 which extends into the valve bonnet having its innermost end received by a slot or key-way 52. With this construction it is not possible for the valve stem to rotate with the operating nut and therefore rotational movement of the nut is converted into reciprocating movement of the valve stem and valve head.

The important feature of this invention consists in the provision of a means to permit the inspection or removal of one of the valve head dies, and at the same time being assured that the other valve head die is in operating position. Thus the operation of the well is not interrupted during this inspection or repair procedure. To accomplish this end each lateral wing of the horizontal section of the valve body is provided with diagonally opposed window openings. For example, the right-hand section 25 has a lower opening 53 and an upper opening 53'.

Threaded studs 54 are formed integrally with the outer surface of the valve body section and inspection plates 55 and 55' are used to cover the window openings, especially during the inspec-

tion or replacement operation. Each plate is provided with peripheral apertures aligned with studs 54 so that the plate may be clamped tightly against the outer surface of the valve body by tightening of the retaining nuts 56. Naturally the cover plates are arcuate in configuration in order to conform with the shape of the outer surface of the horizontal section of the valve body.

The left hand section 30 of the valve body is provided with identical window openings 57 and 57'. Each of these openings is respectively closed by a cover plate 58 and 58'. Thus it will be seen that if the die 37' has been damaged by matter suspended in the flowing oil, the valve head can be moved to the left so that die 37 is placed into operation. Cover plates 58 and 58' may then be removed to permit inspection of die 37'. If replacement is required the die may be forced through opening 57 by striking the upper surface with an appropriate tool inserted through the window opening 57'. A new die may then be inserted and cover plates 58 and 58' replaced. The valve is then completely repaired without interruption of the well operation, and naturally the same inspection or repair treatment may be given die 37, primarily moving the valve head to the right as shown in Fig. 1.

In order to provide proper lubrication and adequate seal protection for the movable valve head I have designed the plunger head as shown in Figures 2 and 3. First of all, a groove or recess 59 in the peripheral surface of the valve head is provided and preferably extends in parallel relationship to the axis of the unit. This groove is located on one side of the receiving end of the spaced valve dies 37 and 37'. A similar groove 59' is located on the opposite side of said receiving ends. These grooves are each provided with an appropriate strip of sealing material, such as neoprene and prevent the possibility of the conveyed fluid by-passing the valve orifices.

On each side of the cylindrical valve head I show a number of overlapping grooves also in parallel relationship to the axis of the unit. Grooves 60 open into the free end of the valve head and extend slightly beyond the transverse center of the unit. By the same token intermediate grooves 61 open into the same face of the valve head, and by extending beyond the center line of the valve head, overlap groove 60. This construction provides additional sealing effect and at the same time adequately lubricates the periphery of the valve head so that the operation of the valve is accomplished with ease.

It is to be noted that the sealing strips extend longitudinally of the valve head and are placed on opposite sides thereof. Each sealing strip is positioned slightly above the lower openings for the dies 37 and extend longitudinally of the valve head beyond the longitudinal extremities of the openings. Grooves 60 and 61 extend longitudinally of the valve head above the sealing strips.

The form of the invention illustrated in the drawing shows one method of assuring that the movable valve head is properly balanced. That portion of the interior of horizontal section 24 not occupied by valve head 35, is completely filled with oil. The horizontal cavity at each side of the valve head is supplied with line fluid. Each section has an opening 62 which is connected by a conveying tube 63 to a small oil reservoir 64. This provides a small storage for oil and is connected directly into the main line by means of pipe 65 controlled by the proper

shut-off valve arrangement 66. Identical communicating structure is located at both sides of the valve head 35. It will of course be understood that this arrangement could also be used to reciprocate the plunger-type valve head 35 by use of a hydraulic pump. By relieving oil from one side of the valve head and pumping oil to the other side either valve die could be moved into operating position.

It will be appreciated that the conventional plunger-type valve is objectionable due to the fact that any shut-down of operation is extremely costly and thus undesirable. The valve dies must be repaired or replaced frequently. For this reason a device such as shown and described in this application provides a far more efficient possibility of equipment than is presently available. The unit can be quickly and easily repaired and more important operation of the well is not interrupted.

I claim:

1. A flow control valve unit comprising generally laterally intersecting sections, one of said sections comprising a main housing, a valve reciprocatingly mounted in said main housing, said valve having spaced transverse openings formed therein, orifices mounted in each of said openings, second orifices mounted in the other of said laterally intersecting sections, said valve being movable in said main housing so as to align any one of the orifices mounted therein with the orifices mounted in the other of said sections, each end of said valve forming an oil chamber with one end of said main housing, grooves formed in said valve extending generally longitudinally of said main housing, a strip of sealing material mounted in said grooves, additional grooves formed in said valve and extending generally longitudinally thereof, some of said last named grooves being in overlapping relationship with other of said last named grooves and some of said grooves communicating with the oil chamber formed at one end of said main housing and the other of said grooves communicating with the oil chamber formed at the other end of said main housing. 45

2. A flow control valve unit comprising generally laterally intersecting sections, one of said sections comprising a main housing, a valve reciprocatingly mounted in said main housing, said valve having spaced transverse openings formed therein, orifices mounted in each of said openings, second orifices mounted in the other of said laterally intersecting sections, said valve

being movable in said main housing so as to align any one of the orifices mounted therein with the orifices mounted in the other of said sections, each end of said valve forming with one end of said one of said sections an oil chamber, grooves formed in said valve extending generally longitudinally of said main housing, a strip of sealing material mounted in said grooves, additional grooves formed in said valve and extending generally longitudinally thereof, some of said last named grooves being in overlapping relationship with other of said last named grooves and some of said grooves communicating with the oil chamber formed at one end of said main housing and other of said grooves communicating with the oil chamber formed at the other end of said main housing, means forming openings in said main housing, removable cover plates forming closures for said last named openings, 10 said valve being movable in said main housing so as to align the openings formed therein with the openings formed in said main housing.

3. A valve unit comprising intersecting sections, one of said sections comprising a main housing, a valve reciprocatingly mounted in said housing and having an opening formed therein, a second opening formed in another of said sections, said valve being movable in said main housing so as to align the first mentioned opening with the second mentioned opening, each end of said valve forming an oil chamber with one end of said main housing, grooves formed in said valve extending generally longitudinally thereof, a strip of sealing material mounted in said grooves, additional grooves formed in said valve and extending generally longitudinally thereof, some of said last named grooves being in overlapping relationship with other of said last named grooves and some of said last named grooves communicating with the oil chamber formed at one end of said main housing and the other of said last named grooves communicating with the oil chamber formed on the other end of said housing. 40
